UNITED STATES PATENT OFFICE.

JOSEPH A. ARTHUR, OF LOGAN COUNTY, WEST VIRGINIA.

RECIPROCATING PROPELLER.

SPECIFICATION forming part of Letters Patent No. 274,693, dated March 27, 1883.

Application filed February 21, 1883. (No model.)

To all whom it may concern:

Be it known that I, JOSEPH A. ARTHUR, a citizen of the United States, residing in the county of Logan and State of West Virginia, have invented certain new and useful Improvements in Reciprocating Propellers; and I do hereby declare the following to be a full, clear, and exact description of the invention, such as will enable others skilled in the art to which

it appertains to make and use the same.

This invention relates to improvements in reciprocating propellers, and in the mechanical movement for operating the same, which has for its object to utilize the weight and muscular power of the operator. This object is attained by the mechanism illustrated in the accompanying drawings, forming a part of this specification, in which—

Figure 1 is a plan view. Fig. 2 is a side elevation with some of the parts broken away. Fig. 3 is a modification of my invention. Fig. 4 is a detail view.

The letter A represents a part of the boat or vessel.

A² indicates a frame which may support the driving mechanism.

A³ is a frame extending over the side of the boat or vessel, and supports the propellers and their operating devices.

C is a platform attached to the rock-shaft E.

H is a spur-wheel having attached to one of its radiating arms the crank D, to which is secured the upper extremity of the pitman E', and the other end is pivoted to the treadle or platform C.

H' is a pinion which gears into the spur-wheel H.

G is the shaft of the pinion H', and is supported in suitable bearings in or attached to the frame B. It is provided with a double crank, G' and G'', and extends across the frame A³, and is journaled thereto by suitable boxes.

J J' are pitmen, attached respectively to the cranks G' and G'' and to the sliding frames U U' U'' U'''.

b are grooves in the frames B and A³, in which the frames U U' U'' U''' are adapted to slide back and forth.

b' b² are hangers, to which are journaled the reciprocating propellers I.

W represents pieces of wood or metal, which

extend from the slides U to U' and from U'' to U''', and thus connect these parts to each other.

I are the buckets or propellers, which are swung on journals attached to the upper part, 55 and are provided with arms O and O', extending therefrom at an acute angle in an upward direction.

R R' are lugs attached to the beams W, and form a support for the rock-shafts Q. 60

P are studs extending upwardly from the shafts Q.

Q' are arms, which curve downwardly from the rock-shafts Q.

f f' are springs, which bear upon the upper 65 portion of the rock-shafts Q' at a part which is cut into an angular shape, and are intended to hold these shafts at the proper angle and for purposes hereinafter described.

F and F' are cranks connected to each other 70 by a horizontal rod, L, and are located on one side of the frame B, through which extend rock-shafts F'' F''', which are supported by suitable bearings, and have attached to their outward extremities the arms M M', which are 75 provided with short arms m m' m'' m''', the ends of which are intended to engage with the studs P, when placed in the proper position, by turning the cranks F-F', and thereby turn the rock-shafts Q, with their arms Q', in such manner that the latter may strike the arms O O' and turn the paddles I to a position which will change the motion of the vessel to a backward or forward direction.

e is a small piece projecting from the hanger 85 b', and is intended for a stop to prevent the propellers I from going too far in a horizontal position.

K is an arm projecting from the frame B, the end of which is intended to strike against 90 the arm O and change the position of the propeller I.

K' is an arm projecting from the frame A³, and is for the same purpose as K.

S' are slots in the frame B, and S are bolts 95 and nuts, by means of which the frame B may be adjusted to different heights, and then fastened to the vessel in a position to give the propellers a smaller or a greater dip.

The cranks G' and G'' and pitman-rods J J' 100 cause the slides U and U'' to move in opposite directions, one forward and the other back.

ward, at the same time. In the forward motion the propeller assumes a nearly horizontal position, while in the backward motion of the slide the propeller is nearly vertical and drives the boat or vessel in a forward direction. To change this it is only necessary to turn the crank F, when the arms M and M' will assume inclined positions to the right or left, and cause the short arms $m m' m'' m'''$ to engage with the studs P P and change the directions of the curved arms Q' in such a manner as to strike against the arms O O' and alter the previous position of the propellers. One portion of the rock-shafts Q is of an A shape, as shown in dotted lines in Fig. 4. The springs bear upon this part, and by this means hold the rock-shafts Q in any position in which they may be placed by the action of the short arms $m m' m'' m'''$.

In Fig. 2 the oscillating platform C is shown in dotted lines, and in Fig. 3 in full lines. The platform C is intended as a standing-place for the operator, who is to place one foot at each end on the curved portion of the platform at the same time that he grasps with his hands the crank-handle D, and as he throws his weight alternately on one foot and then on the other and turns the crank D with his hands, a rotary motion is given to the wheels H and H', and the slides U' U U'' U''' are caused to reciprocate by the action of the cranks G' and G'' and their pitman-rods J and J', together with the propellers I.

Having described my invention, what I desire to secure by Letters Patent and to claim is—

1. In a reciprocating propeller, the combination of cranks F F' and connecting-rod L with rock-shaft F'' and arms M M', said arms serving to support the feathering mechanism of a reciprocating propeller, substantially as described, and for the purposes set forth.

2. In a reciprocating propeller, the combination of shaft G, cranks G' G'' on said shaft, connecting pitman-rods J J', with slides U U' U'' U''', which carry the paddles, and have lugs R, adapted to hold the rock-shafts Q in the specified relation to the paddles, substantially as shown and described, and for the purposes set forth. 45

3. In a reciprocating propeller, the combination of the propellers I, having arms O' O, with the rock-shafts Q, having studs P and curved arms Q', with which the arms O O' engage, substantially as described, and for the 55 purposes set forth.

4. The frame B, carrying the reciprocating propeller and the operative mechanisms, substantially as described, and having slots S', combined with retaining-bolts or similar devices operating in said slots, whereby the frames and propellers may be raised or lowered, as stated. 60

5. The oscillating platform and the hand-wheel H, connected together by a pitman, and operating the propeller by means of connecting mechanism, substantially as described, said propeller being made to reciprocate with the frame and be feathered thereon by mechanism substantially as stated. 65

6. A reciprocating slide carrying a bucket or buckets swiveled thereto, said buckets having arms extending upward to engage with one or the other of the arms on the rock-shaft Q, to be feathered in one direction or the other, all being in combination substantially as stated. 70

In testimony whereof I affix my signature in presence of two witnesses.

JOSEPH A. ARTHUR.
